Fig. 3.

UNITED STATES PATENT OFFICE.

HARRY BENJAMIN GOLDMAN, OF PITTSBURGH, PENNSYLVANIA, ASSIGNOR OF ONE-HALF TO MARSHALL BROTHERS CO., OF PITTSBURGH, PENNSYLVANIA, A CORPORATION OF PENNSYLVANIA.

ELEVATOR SYSTEM.

Application filed May 26, 1923. Serial No. 641,727.

To all whom it may concern:

Be it known that I, HARRY B. GOLDMAN, a citizen of the United States, residing at Pittsburgh, in the county of Allegheny and State of Pennsylvania, have invented certain new and useful Improvements in Elevator Systems, of which the following is a specification.

My invention relates broadly to elevators, and more particularly to an automatic system for insuring the leveling of the elevator platform with the plane of the floor surface of each story of a building throughout the height of the elevator hatchway.

One of the objects of my invention is to provide a control circuit for an elevator by which the automatic leveling device insures the stopping of the car with its platform level with the plane of the floor area adjacent the hatchway.

Another object of the invention is to provide a control circuit in an elevator system whereby the automatic leveling device is operative only when the elevator controller is in the position of slow speed, at which time the elevator is normally retarding acceleration and tending to seek a position of rest, while the leveling device is inoperative when the elevator is in intermediate or other speeds up to high speed.

Another object of the invention is to provide a circuit arrangement for a leveling device operative independent of the opened and closed position of the elevator doors so that the elevator platform remains level with a floor under varying conditions of load which may occur with the running of heavy tonnage trucks on or off of the elevator platform with the elevator doors wide open.

A further object of the invention is to provide independent up and down leveling devices and separate circuit arrangements whereby up and down cams adjustably mounted on the side of the hatchway cooperate with the leveling devices in such manner that if the car overruns the landing in the up direction, the down leveling device cooperates with the down cam, running the elevator down level with the floor, and conversely, if the elevator has gone below the floor the up leveling device cooperates with the up cam, thereby bringing the car up level with the floor.

Another object of the invention is to provide an elevator controller which may be positioned at the will of the operator of the elevator to control the movement of the car manually with automatic control circuits auxiliary to the controller to automatically level the car within a given zone at a floor landing independent of the elevator controller.

Other and further objects of my invention will be understood from the following specification by reference to the accompanying drawings. In Fig. 1 is a schematic or across the line wiring diagram of a single speed elevator equipment with slow down and dynamic braking showing the electrical connections for my automatic leveling device. The leveling device has been shown in perspective view to more clearly set forth the invention. Fig. 2 is a side elevation of the leveling device shown partly in section and Fig. 3 is a plan view of the leveling device with parts broken away.

The specific construction of my automatic leveling device is the subject matter of my copending application, Serial Number 641,726, filed May 26, 1923.

My leveling system is adapted for installation on various types of elevators. The application of the leveling system will be considered in connection with a direct current elevator control with the elevator equipment, including panel board, located at the top of a hatchway with the elevator operative up and down the hatchway by movement of the elevator controller within the car.

Fig. 1 is a simplified diagrammatic showing of a direct current elevator control circuit used to illustrate the operation of my leveling device. The elevator controller is represented at 60 with control handle 61 carrying rotatable switch blade 62 with contact faces 63 and 64 cooperating with contacts within the controller. The leveling device 14 has been represented in perspective view in Fig. 1 cooperating with adjustable cams 6 and 7 supported on a vertical angle iron 5 on the side of the hatchway. The control apparatus which is normally positioned on the elevator control panel at the top of the hatchway adjacent the elevating mechanism has been reduced to a simplified elemental form for clarifying the description

and each of the controls represented by a reference character as hereinafter described. The terminals of the system are represented at L^{1+} and L^{2-} .

5 With the elevator in the condition of rest, the "up" circuit may be traced from connection 65 on L^{1+} through the interlock on the accelerating unit marked "AR," with shunting resistance 86 through the fuse 66, 10 through the overspeed governor switch 67 with terminals X^4 and X^3 , through the final limit switch "Up" indicated at 68 with terminals X^3 and X^2 , through the final limit switch "Down" indicated at 69 with terminals X^2 and X^1 through the car safety switch 70 with terminals X^1 and X through "FB" at 71, magnets U^2 and U^1 of reversing switch 72 through the stop switch "Up" indicated at 20, to the switch contact 2 on the 15 elevator controller 60. A tap is taken off 20 switch 73 to the "Up" leveling switch contacts connected by wires 29 and 30, then through the emergency leveling switch 74 through the final limit "Down" 75, having terminals N 25 and N^1 , through final limit "Up" 76, having terminals N^1 and N^2 through the fuse 77 to the opposite terminal of the system L^{2-} . In following this circuit it will be seen that the "Up" leveling switch 25 is open and that the 30 controller 61 is in stop position, so that it is not possible for the circuit from L^{1+} to L^{2-} to be completed until the "Up" leveling switch 25 is depressed when the elevator is in the leveling zone and when the wheel 10 on the "Up" switch 25 would rest on the "Up" cam 7. This would only occur if the 35 elevator were below the floor level.

The leveling apparatus is contained within cabinet 14 supported by an angular bracket 12 on the elevator in such a position that the down roller 9 will contact with the down cam 6 and the up roller 10 will contact with the up cam 7, the cams being secured on angle iron 5 which runs along the vertical height of the hatchway. The roller 9 is supported on switch arm 43 to cause contact 46 to close leaf spring contacts automatically controlling the down elevator circuit through wires 47 and 48, each of which connects to separate leaf spring contacts which are shorted by the switch contact 46. The up roller 10 is carried by the switch arm co-operating with the switch 25 with contact 28 at its extremity and adapted to be forced between contacts closing a circuit between wires 29 and 30 which connect to the separate contacts controlling the up elevator circuit. The leveling magnet 53 or slow speed interlock is connected in the circuit by means of wires 53^a and the armature 55 of this magnet has an extended arm arrangement to close the circuit between leaf springs to which wires 88 and 89 are connected, so that when the car is in intermediate or high speed the leveling device will be pulled back 40 about pivot 17 out of alignment with the cams.

Reference will now be had to the "Down" circuit: With the elevator in the condition of rest the "Down" circuit may be traced from connection 65 on L^{1+} through the interlock on the accelerating unit marked "AR" with shunting resistance 86 through the fuse 66, through the overspeed governor switch 67 with terminals X^4 and X^3 , through the final limit switch "Up" 68 with terminals X^3 and X^2 , through the final limit switch "Down" 69 with terminals X^2 and X^1 through the car safety switch 70 with terminals X^1 and X through "FB" at 71, 75 through the reversing switch magnets D^1 and D^2 of reversing switch 72 through the stop switch "Down" 11 to controller contact 1. Tap 78 is taken from this connection to the down leveling switch 43 through wires 47 and 48, then through the emergency leveling switch 74, the final limit "Down" 75 having terminals N and N^1 through final limit "Up" 76, having terminals N^1 and N^2 through the fuse 77 to the opposite side of the system 80 at L^{2-} . This circuit with the car at rest as illustrated is also open and nothing will happen unless the down leveling switch 43 is depressed by roller 9 resting on the down cam 6, which would occur were the elevator 85 above the floor.

Now starting from L^{1+} , through wire 85, to the wire which goes to the interlocks 84 on the bottom of the reverse switch, it will be noted that these interlocks are normally 100 open when the elevator is at rest, and since there is an interlock on the bottom of each reverse switch, either one or the other reverse switch must be closed in order to close the circuit from either one or the other of 105 the interlocks. The circuit continues through "DB" through wires 88 and 89 to the slow speed interlock contacts on the leveling device which are only closed when the leveling magnet 53 is energized and its armature 55 pulled back. An emergency high speed switch 87 is shunted across the slow speed interlock contact wires 88 and 89 on the leveling device. The circuit continues through the slow down switch "Up" 40^a and slow down switch "Down" 40^b to the car switch contacts 4 and 3 respectively which are open in the stop position of the elevator as illustrated. In the diagram with the elevator in the position of rest the circuits and contacts, interlocks, etc. are broken in several places to insure de-energization of all circuits when the rollers 9 and 10 are between the cams 6 and 7. The circuit arrangement 115 is such that unless the leveling magnet 53 closes, thereby pulling back the leveling switches, the slow speed interlock on the bottom of the leveling magnet cannot be closed; but of course, if the leveling magnet 120 closes, the leveling switches cannot be op- 125 130

erated by the cams on the side of the hatchway. It is only in the closed position of the leveling magnet that the slow speed interlock can be closed, thereby operating the elevator at high speed.

Considering the elevator at the first floor in a hatchway and that there are five floors and it is desired to travel to the third floor at full speed: In the diagram the up circuit can be traced from L^2 through the fuse 77, the final limit switch "Up" 76 with terminals N^2 and N^1 , the final limit switch "Down" 75 with terminals N^1 and N through the door contacts 91 opened and closed according to corresponding positions of the door of the elevator, to the bridged car switch contacts 80 and 81, then through the switch blade 62 having face contacts 63 and 64. The switch controller 61 is thrown in the dotted line "Up" position 83 and the circuit is completed through switch contact 2, the stop switch "Up" 20, windings U^1 and U^2 on reverse switch 72, through 71, 70, 69, 68, 67, 66, and the interlock on the accelerating unit "AR" to connection 65 on the line L^{1+} . The circuit is also completed from L^2 through 77, 76, 75, bridge switch contacts 80 and 81, through the switch blade 62, switch contact "LM" through wires 53^a, the leveling device magnet 53, and to the left to wire 85, up this wire and over to connection 65 on line L^{1+} . This circuit causes the leveling device magnet 53 to be energized and throws the leveling switches back and closes the slow speed interlock through wires 88 and 89 on the leveling device.

A circuit is also completed from L^2 through 77, 76, 75, 91, car switch contact 81, through the wiping contact 64, switch contact 4, through the slow down switch "Up" 40^a which has been closed down through the slow speed interlock magnet on the leveling device, through wires 88 and 89, as aforesaid, through "DB", through the "Up" interlock on the bottom of the reverse switch 84 to conductor 85 over to connection 65 on line L^1 . The "DB" magnet referred to is representative of a spring closed switch which instead of closing when the current is applied to its coil acts in the reverse order and opens, thus opening armature shunt slowdown resistance and by means of an interlock (not shown) causes "AR" magnet to be energized, thus bringing the motor up to normal speed.

The "AR" magnet referred to as energized with the switch in position 83 actuates the accelerating fingers on the controller which cut resistance out of the driving motor armature, thereby bringing the motor up to its normal speed.

The several instruments employed in this control circuit are mounted as usual upon the elevator control panel. When the first finger goes in on the accelerating unit the

interlock on the accelerating unit marked "AR" opens, thereby inserting resistance represented at 86 in the circuit which includes 71, U^2 and U^1 , 75, 76, and 77 over to the other side of line L^2 . The resistance 70 75 across the interlock on the accelerator unit is interposed to prevent the operation of either U^1 , U^2 , and "FB", or D^1 , D^2 and "FB" should the accelerating fingers not be in open position.

All of these circuits previously described have been energized by movement of the controller 61 in the position 83. The elevator is now presumed to be going at full speed up the hatchway. When the elevator reaches the third floor landing, the car switch is brought to the central position. In bringing the car switch to the central position 61, the first contact released is the "LM" finger in the car switch which de-energizes 80 the leveling device magnet 53, thereby allowing the leveling switch arms controlling the switches 25 and 43 to go forward. The next contacts, or fingers released or disconnected, are the bridged fingers 80 and 81 and 2, 90 which are disconnected simultaneously.

There is sufficient space between the "LM" and 2 contact, as well as the "LM²" and 1 contact, to insure a sufficient time interval 95 between the opening of the "LM" finger and 2 finger, to insure the leveling switch arms always being in the operating or extended position for they drop immediately to operative position under gravity action, before either 1 or 2 fingers are disconnected. Furthermore, as soon as the leveling magnet is de-energized, the slow speed interlock on the leveling device is immediately open, thereby assuring that the elevator is always 100 on slow speed when the leveling switches are in the operating position, or in other words, when the leveling switches might be resting on either the "Up" or "Down" cam, for the leveling operation is only necessary 105 in the slow speed position when the elevator is normally retarding acceleration and seeking a position of rest.

Now, if the elevator has come exactly level with the floor, nothing happens because the leveling switch wheels 9 and 10 are in the depression between the two cams and all circuits are de-energized. However, if the car were to over-run the landing in the "Up" direction, the wheel 9 of the "Down" leveling switch would then rest on the "Down" cam 6 operating the down control circuit to automatically run the elevator down level with the floor, and conversely, if the elevator has become below the floor, the wheel 10 of the "Up" leveling switch would rest on the "Up" cam 7, operating the up control circuit automatically bringing the car up level with the floor.

In considering the up circuit, the connections between the contacts 81 and 2 are 130

connected in shunt to the "Up" leveling switch so that if the elevator were going up on slow speed, both leveling switches being out, the cams would be actuated in the following order:—The "Up" switch 25 would strike the "Up" cam, first run off it, opening its circuit, and if the car still continued to travel up at the slow speed, the "Down" leveling switch 43 would be striking the "Down" cam, establishing its circuit to the "Down" magnet, but nothing would happen here, because there is a mechanical interlock between the "Up" and "Down" switches, so that if the "Up" switch were in, as it is in this case, the "Down" direction switch could not come in, due to the fact that the mechanical interlock would be holding it open. The mechanical interlock is a device placed between the "Up" and "Down" direction switches, so arranged that when either switch is closed, it carries with it one-half of the "walking-beam" mechanical interlock, forcing the other end of the interlock out against the opposite switch, effectually preventing both switches being in at the same time.

The circuit illustrated has been described as in a single speed slow down and dynamic braking elevator system. The use of the term "single speed" as known in the art may be somewhat misleading in considering my description herein, but there is logical reasoning for this apparently misleading description. With the single speed elevator equipment, slow down is obtained by inserting resistance in the armature circuit of the normal single speed motor, so that while the motor is really a single speed motor, slow down can be obtained with this type of control, by means of inserting resistance in the armature circuit and using an armature shunt resistance. With the two speed equipment, three speeds are really obtained because slow down can be secured by inserting resistance in the armature circuit as well as strengthening the field of the motor in two or three steps or more, depending upon the design of the motor. Motors of the two-speed type are motors which are designed for adjusting their speed by means of field control, but not by inserting resistance in the armature and are known as adjustable speed motors. The single speed motor is one which has a set speed, and can only be reduced in speed by inserting resistance in the armature circuit and by means of an armature shunting resistance or a combination of both.

Referring more particularly to the operation of the leveling devices, when the car switch 61 is thrown into the up direction indicated by dotted line 83, first a circuit is completed through switch contacts 81 and 2, the current flowing through 20, U¹, U², 71, 70, 69, 68, 67, 66, through the interlock

on the accelerating unit "AR" to connection 65 on the line L¹⁺. The elevator is now running up the hatchway on slow speed. Contacts 2 and 81 are the first contacts bridged by the switch blade 62. The leveling devices are operative, for no current has been sent through the leveling device magnet 53 which will only occur when face 63 of switch blade 62 enters upon switch contact "LM."

The elevator will now be running up the hatchway slowly. When it reaches the next floor the up leveling switch roller or wheel 10 will rest upon the up cam, thereby closing the contacts rocking back the leveling device on pivot 17 and keeping the contacts closed even though car switch handle were returned to center, and of course, if the contacts on the "Up" leveling switch are closed, current will then flow from 81 down to the two center contacts on the "Up" and "Down" leveling switches, and since the "Up" contact is closed back up to 2, through 2, 20, U¹, U², 71, 70, 69, 68, 67, 66, and the "AR" interlock, to L¹, thus holding closed the "Up" direction circuit and energizing the entire up circuit thereby running the car up until the "Up" roller runs off the "Up" cam, when both wheels 9 and 10 will be in the depression between the "Up" and "Down" cams when the circuit is de-energized and the car brought to rest level with the floor.

However, should the car switch not be thrown to the off position, the first cam struck going up slowly, would be the "Up" cam, closing the contacts on the "Up" leveling switch holding them closed, and if the elevator continues on past the depression between the cams, the "Up" leveling switch contacts would be open, and if the elevator kept on traveling slowly, the roller on the "Down" leveling switch would then rest or roll on the "Down" cam, thereby establishing a circuit from N through 74, down through wire 48 to the center contacts, between the "Up" and "Down" leveling switches, through the "Down" contacts, wire 47 to contact 1, through 11, through D², D¹, through 71, 70, 69, 68, 67, 66, and the "AR" interlock to L¹, thereby energizing D¹ and D², but since the car is traveling up, U¹ and U² switches are in operative position, carrying with it the aforementioned mechanical interlock, which effectually prevents the closing of D¹ and D² switches, even though their coils are energized at the same time as U¹ and U².

However, if the car switch was returned to center 61 before the roller of the "Down" leveling switch were off the "Down" cam, instantly D¹ and D² switches would close starting the elevator down until both wheels rested in the depression between the cams and the car came to rest.

The down position of the controller is indicated in dotted lines 90. The principle involved in the system when the elevator is traveling in a down direction and stopping at various floors, is the same as described for the up direction of travel, with the exception that the down roller is the first to engage with the down cam to bring the car level with a floor when both the up and down rollers 9 and 10 are between the up and down cams. Leveling contact LM² is employed to control the energization of leveling magnet 53 when traveling in this direction.

15 While I have described my invention in a certain illustrative embodiment, it will be understood that various changes may be made. In the circuit illustrated the door contacts 91 are placed in the manual controller circuits but not in the automatic leveling device circuits, so that the elevator is automatically leveled independent of the opened and closed position of the elevator doors. I intend no limitations upon my invention other than those imposed by the scope of the appended claims.

What I claim is:

1. In an elevator system, an elevator, an elevator controller, a plurality of control circuits arranged to be energized when said controller is moved to different positions, a plurality of separate leveling devices each separately electrically connected to said control circuits, door contacts adapted to be opened and closed in accordance with corresponding positions of the door of said elevator, said contacts being connected in series with said control circuits but independent of said leveling device circuits 40 whereby said leveling devices remain operative independent of the position of said door contacts.

2. In an elevator system, the combination of a controller, a plurality of circuits arranged to be energized when said controller is moved to various positions, a leveling device, and electromagnetic means whereby said leveling device is rendered inoperative when said controller is moved to certain of said positions and operative when said controller is moved to another of said positions and a separate circuit adapted to be closed when said leveling device is rendered inoperative.

3. In an elevator system, the combination of an elevator hatchway, cams mounted on said hatchway, a leveling device mounted on an elevator, switches pivotally mounted on said device and adapted to be operated by said cams, a circuit arrangement for controlling the operative and inoperative positions of said switches, and a separate electrical circuit adapted to be closed when said switches are moved to inoperative position.

4. In a leveling system for elevators, the combination of a hatchway, an elevator operative in said hatchway, a controller in said elevator for operating said elevator at a plurality of speeds including slow speed, a plurality of pairs of cams on the side of said hatchway, a leveling device carried by said elevator adapted to cooperate with said pairs of cams, said leveling device comprising a pair of independently controlled switches, electrical means for preventing the cooperation of said leveling device with said cams when said elevator is operated at any speed greater than slow speed and mechanical means for causing said leveling device to cooperate with said cams only when operated at slow speed.

In testimony whereof I affix my signature.
HARRY BENJAMIN GOLDMAN.
